PROJECTION OF LIGHT

George Kettelwell Harkness, Rochester, and John Maxwell Harkness, Dartford, England, assignors, by mesne assignments, to Berthold A. Cronson

Application December 21, 1931, Serial No. 582,414
In Great Britain July 11, 1931

10 Claims. (Cl. 240—45)

This invention relates to the projection and transmission of light, and has for its object to provide improved means whereby the projected or transmitted light may be controlled in intensity or colour.

The invention, while of broad application, is especially applicable to anti-dazzle or dimming devices for the lamps or wind screens of motor vehicles or aircraft.

According to the invention the light which is to be controlled in intensity or colour is projected or transmitted through juxtaposed plates of transparent material such as glass, which plates are mounted to permit their separation to a determined or variable degree for the formation between the adjacent surfaces of a cavity or cavities into which is introduced a liquid or gaseous medium adapted to obstruct the passage of light to a determined degree or to impart a colour to light transmitted through it.

According to the invention, moreover, the plates may be mounted with an initial separation providing between the adjacent surfaces a cavity of a thickness such that when it is filled by the liquid or gaseous medium a determined maximum obstruction or colouration of the transmitted light is secured.

According to the invention, also, a plurality of pairs of such plates may be juxtaposed for the transmission of the light through them in succession, and the liquid or gaseous medium may be caused to pass between the plates of any one pair or of more than one pair simultaneously for the obstruction of the transmitted light to a determined degree, or to impart to the transmitted light any desired colour or combination of colours.

According to the invention, moreover, certain or all of the transparent plates may be provided in the form of lenses.

According to the invention, moreover, it is advantageous to employ as the obstructing medium a liquid or solution of low freezing point such as alcohol.

According to the invention, also, the introduction of the liquid or gaseous medium between the plates of the pair or pairs of plates may be effected under pressure exerted upon the liquid or gaseous medium to a variable degree, according to the desired intensity of colour to be imparted to the transmitted light.

According to the invention, moreover, means may be provided for causing the admission or withdrawal of the liquid or gaseous medium to and from the cavity or cavities between the plates, comprising a flexible diaphragm or piston that

may be adapted for instantaneous operation under the action of a spring or like operating element, whereby, upon a movement of the diaphragm or piston in one direction, the contents, or part of the contents, of a container may be forced into the cavity or cavities between the plates, or be immediately withdrawn on the return movement of the diaphragm or piston.

The invention is diagrammatically illustrated by way of example in the accompanying drawings.

Figure 1 is a cross-section of a vehicle wind screen constructed according to the invention, the transparent plates being shown in contact or in the inoperative position.

Figure 2 is a cross-section of the vehicle wind screen shown in Figure 1, with the transparent plates separated by the liquid medium.

Figure 3 is a partial front elevation of the wind screen shown in Figures 1 and 2.

Figure 4 is a sectional elevation of an apparatus for effecting the introduction of the liquid medium between the transparent plates or effecting its withdrawal therefrom.

Figure 5 is a diagrammatic elevation illustrating the application of the invention as an anti-dazzle or dimming device to the head lights of motor vehicles.

Figures 6, 7 and 8 are cross-sectional views of modified arrangements of the transparent plates of the apparatus according to the invention.

In carrying the invention into effect in the production of a wind screen for motor vehicles in the manner illustrated in Figures 1 to 3 of the accompanying drawings, a pair of plates *a* of glass are mounted in juxtaposition in a rubber seating *b* carried in a framing *c* of metal or other suitable material. The plates *a* are bevelled along the inner or adjacent edges as at *a'* so that a cavity of triangular cross-section is formed around the outer edge. The rubber seating is formed advantageously as an open rectangular body or annulus of rubber adapted to be fitted within the channel section of the frame *c* and having on the inner face grooves or channels *b'* moulded or otherwise provided of a cross-sectional shape corresponding to that of the peripheral edges of the transparent plates, but with the material intermediate the grooves or channels cut away to leave a cavity *d* of triangular section between the bevels of the plates when they are in position within the seating. The rubber seating is, moreover, provided of a material having a considerable degree of elasticity that will permit the separation of the plates under a relatively low pressure as exerted by a fluid medium introduced between

the said plates. To facilitate the movement of the plates the inner surface of the rubber seating is bevelled or cut away at the lateral edges as at b^2 so that the resistance offered to the movement of the plates is thus reduced, since the rubber may extend outwardly in the direction normal to the plates to fill the spaces or recesses b^2 . At one or more points along the upper limb of the rubber seating b there are provided inlet passages b^3 which are connected by rubber conduits b^4 leading outwardly from the frame c and connected to a suitable reservoir of a liquid medium which can be subjected to the necessary pressure to force the liquid by way of the passages b^3 into the cavity d and thus between the plates a , whereby the plates are separated to the extent determined by the pressure exerted by the liquid and the windscreen is clouded or coloured to a corresponding intensity according to the nature of the liquid used. Thus, the liquid may be a transparent violet liquid which in a thin film, as determined by close adjustment of the plates a , exhibits a slight trace of violet colouration, whereas, when the plates are moved apart to a greater extent and the body of liquid present is of greater thickness, the colouration is of correspondingly greater intensity.

Any suitable device may be employed for the purpose of exerting the pressure necessary to force the liquid medium between the plates a . Thus, a simple plunger device may be provided in which the plunger is operated by a hand lever or the like, or the plunger may be adapted to be operated by a screwed controlling member, whereby any degree of pressure may be exerted through the plunger upon the liquid to be introduced between the plates. A preferred form of pressure device is illustrated in the accompanying drawings in Figure 4. A cylindrical container or reservoir e for the liquid medium is mounted at a convenient position, for example, upon the dash board of the motor vehicle. The upper end of the said container is closed by a flexible diaphragm f which is clamped at the periphery upon the end of the container by a downwardly depending flange provided upon a cover e^1 which is secured in position by means of a holding ring and bolts. Alternatively, the diaphragm may be clamped between flanges provided respectively on the upper end of the container and the lower end of the cover. The reservoir e is connected by a conduit e^4 with the conduits b^4 leading to the cavity d around the plates a . The cover plate e^1 is provided on the inner periphery with a seating ring having a peripheral groove on the inner surface or seating blocks e^2 in which is seated a dished plate spring or leaf spring g . The said spring is secured at the centre to a control rod g^1 which extends through a guide sleeve e^3 in the cover plate e^1 and is provided at the outer end with a knob or handle g^2 . At the inner end the rod g^1 is engaged with the diaphragm f by means of a pair of washers f^1, f^2 , between which the material of the diaphragm is engaged and secured in position by such means as nuts g^3 screwed upon the rod g^1 . Such a device is adapted for instant control, since when the knob or handle g^2 has been pressed inwards to cause the spring g to be deflected past the dead point, the consequent movement of the diaphragm f continues notwithstanding the withdrawal of the hand from the knob g^2 . There is thus produced what may be termed a prolonged pumping action while the operation is substantially instantaneous. Under the pressure exerted by the dia-

phragm it will be understood that the liquid contained in the container e is forced into the cavity d surrounding the plates a and under the pressure exerted passes between the plates, thus providing the desired dimming effect. When it is desired to restore the plates to the initial position without liquid between them, it is only necessary that the knob or handle g^2 should be withdrawn until the spring g has again passed the dead point on the outward stroke. The liquid is then withdrawn from between the plates a under the suction imposed by the diaphragm g . Such diaphragm device may be used either as a suction or pressure pump for the pumping of liquids or gases generally.

The frame c is conveniently mounted upon the usual standards or supports c^1 by such means as rods c^2 which are received into a tubular member c^4 fitted around or forming part of the upper limb of the frame c . The position or angular adjustment of the windscreens is determined by adjusting screws c^5 adapted to engage the rods c^2 .

Figure 5 of the accompanying drawings illustrates the application of the invention as an anti-dazzle device to the head lights of motor vehicles. The head lights h are provided in the manner before described, in place of or in addition to the usual front glass or lens, with a pair or pairs of plates such as a to which a liquid medium is supplied by way of a conduit h^1 from the pressure device e mounted upon the dashboard.

It will be understood that while in certain applications of the invention it is desirable to maintain the transparent plates with their adjacent surfaces initially in contact, it may be desirable in certain applications to maintain them with a determined initial distance or space between them and to permit such space to be increased in width upon the introduction of the liquid or gaseous medium into the said space.

According to a modification of the construction as illustrated in Figure 6 of the drawings, in the place of the pair of plates a hereinbefore described, there may be provided two plates i suitably mounted in fixed positions in the carrying frame j , and a third plate k which is movable within the space between the plates i , being supported by a flexible rubber or like seating l . Liquid may be supplied to the exterior of the said seating by way of a conduit m and may enter into the space between one of the plates i and the plate k by way of an orifice or orifices l^1 so that the desired colouration or obscuring of the light transmitted through the plates is secured to a degree that is determined by the volume of liquid or gaseous medium forced into the said space and the consequent movement of the plate k from its middle position towards the second plate i . Such a construction, however, may be modified by dividing the cavity around the exterior of the seating l into two compartments, one of which communicates with the space between the plate k and one of the plates i , and the other of which communicates with the space between the plate k and the other plate i . If the said compartments are respectively connected with containers of liquids of different characters, the device may be employed either for imparting one or other or both of two colours to the transmitted light, or for imparting on the one hand a colour to the transmitted light or for obscuring the light to a greater or less extent.

In the use of the apparatus according to the invention for advertising or for the production of stage or screen lighting effects, a construction

such as that diagrammatically illustrated in Figure 7 may be employed. In this construction a series of pairs of plates *a* such as those described with reference to Figures 1 to 3 are set co-axially 5 in a common frame *n*, and the cavity *d* surrounding each pair of plates communicates by a corresponding conduit *o* with a container containing a liquid of a particular colour or character, each of the said containers being provided with a pressure 10 producing device such as that hereinbefore described, or being connected to some other convenient source of pressure such as a pump in such manner that any one or other of the containers may be subjected to the pressure either individually or collectively. By such means any one or 15 other or any combination of the pairs of plates *a* may be flooded with the corresponding liquids, with consequential colouration or other effect upon the light transmitted through the series of 20 pairs of plates.

It will be understood that any convenient and suitable liquid or gaseous medium may be used for the purpose of the invention. In the application, however, of the device to such purposes as 25 the windscreens and head lamps of motor vehicles, it is desirable that a liquid or solution of low freezing point, such as alcohol, should be used.

It will further be understood that it is immaterial to the invention whether the containers for 30 the gaseous or liquid medium be adjacent to the pairs of transparent plates or otherwise. It is also possible for the control to be effected from a distance by mechanical, electrical, hydraulic or pneumatic means. Such distant control is especially desirable in the case of the application of 35 the invention to stage or screen lighting effects.

It will further be understood that the invention is not limited to the particular constructions and 40 details of construction hereinbefore described. Thus, instead of providing pairs of plates each of which is capable of movement, one of the said plates may be fixedly mounted and the desired separation secured by movement of the other.

The invention also comprises the use of any 45 means for mounting the transparent walls in a manner permitting their outward movement, and while the invention comprises the means for causing their separation under the pressure applied to the liquid admitted between the walls, the admission 50 of the liquid may be effected by movement imparted to the walls, and the liquid may pass into position between the transparent walls under pressure normally maintained, or by gravity, or the pressure may be applied upon the gaseous or 55 liquid medium simultaneously with movement imparted to the movable transparent walls.

As represented, for example, in Figure 8, one of the transparent plates *a* is of fixed position in a suitable mount *p*, while the other of the plates 60 *a* is movable relatively thereto and for the purpose is carried in a mount *q* which is connected to the mount *p* by a flexible element forming the closure of the cavity between the edges of the plates. The mount *q* is provided at intervals 65 around the periphery with studs which extend through inclined slots *r* provided in an operating element *r* formed as a ring which is rotatable through a certain angle with respect to the mount *q*, such rotation being effected by suitable means.

70 Thus it will be understood that the admission of the gaseous or liquid medium into position between the transparent walls may be effected from a relatively distant point. Or again the reservoir or container for the gaseous or liquid medium 75 may be disposed adjacent the transparent walls,

and the control of movement of the transparent walls may be effected by mechanical, hydraulic or pneumatic means, a simple method being Bowden or other similar transmission wire. A series of transparent walls may be provided so mounted that cavities may be provided between them within which a liquid or gaseous medium such as hereinbefore described may be admitted.

It will be understood that in the use of liquid a colour soluble in the liquid used may be employed that is adapted to dim the light transmitted through it to the extent desired, whereby only part of the light from the source is transmitted. It will be understood that colours soluble in the liquid used are advantageously employed.

No limitation is involved to any particular colours, nor yet to the particular density of the colour or optical effects secured. Furthermore no limitation is involved to the particular means of mounting the transparent walls within an elastic packing, nor yet to the shape of the walls. It is, however, preferred to employ elastic or india rubber packing, such as hereinbefore described in which grooves are moulded in the packing for the insertion of the edges of the walls or plates of glass or other material employed. These grooves may be provided of an angular section corresponding to the form of the edge of the glass walls or plates employed, the angular section at the edge being so formed in relation to the section of the groove that while the glass or plate may be readily inserted so that its edges are inserted in the elastic packing, a perfectly liquid or gas tight joint is thus provided. It will, however, be understood that any other means of providing a gas or liquid tight joint may be employed that will permit of the relative movement of the transparent walls or plates employed.

The invention however comprises the alternative of rendering an intermediate transparent wall or plate movable, while mounting the outer transparent walls or plates immovable. In this way the intermediate wall or plate may be mounted by flexible means in the manner of a diaphragm, 115 the intermediate wall or plate being mounted within the frame to which a flexible gas or liquid tight material is connected, the outer end of which is similarly secured to the surrounding frame. Any other means of mounting the respective fixed and movable transparent walls or plates 120 may be employed. The transparent walls or plates may take the form of lenses or sheets of glass having plane faces.

We claim:

1. In an intensity control means for light, the combination of a pair of transparent juxtaposed plates arranged substantially parallel to each other, a yielding seating member for receiving the edges of said plate to form a seal about the edges thereof and for yieldingly urging said plates toward each other with a sufficient force to move the same into engagement with each other, and fluid pressure means for introducing fluid under pressure between said plates for filling the space between said plates with a fluid and for moving said plates away from each other to vary the thickness of the fluid layer therebetween.

2. In an intensity control means for light, the combination of a pair of similarly shaped transparent plates arranged in juxtaposed contacting relation with each other, a substantially imperforate peripheral member of relatively high yielding properties embracing the edges of said plates 145 and forming a seal to prevent fluid which may

- be introduced between said plates from being lost but at the same time permitting said plates to be yieldingly moved away from each other against the resilient action of said member which embraces said edges and holds said plates normally in engagement with each other, and means for introducing fluid under pressure between said plates to move said plates outwardly away from each other against the action of said resilient means.
3. In an intensity control means for light, the combination with a pair of transparent plates, of a relatively soft pliable imperforate yielding member grooved to receive the peripheral edges of said plates and form a seal therefor, said yielding member also having sufficient resiliency to urge said plates normally into contact with each other, a fluid pressure conduit leading through said member, and a fluid pressure supplying means for supplying fluid under pressure to said conduit whereby the fluid under pressure enters between said plates and moves said plates away from each other, said fluid which is introduced between said plates having light modifying propensities.
4. In a light modifying device, the combination with a plurality of transparent plates set in juxtaposed positions and through which the light is directed, a seating element in which said plates are mounted to be relatively movable in a direction toward and from each other, a fluid medium supplying means for supplying fluid medium between said plates and for forcing said plates away from each other, and a pressure creating means operatively connected with said fluid medium supplying means movable to an operative position in which a predetermined amount of the fluid is between the transparent plates and to another position in which a lesser quantity of fluid is between said transparent plates, operator-controlled means for moving said pressure creating means to and from either of said positions, and means automatically operable for insuring that said pressure creating means is moved to and held in either one or the other of said positions and no other after said operator-controlled means is actuated to move said pressure creating means to a position in proximity to either of said positions.
5. In a light modifying device, the combination with a plurality of transparent plates set in juxtaposed positions and through which the light is directed, a seating element in which said plates are mounted to be relatively movable in directions toward and from each other, means for supplying a fluid medium between said plates to spread said plates and occupy the space therebetween, a container for the fluid connected to said seating, a flexible diaphragm in said container forming with a portion of the container a variable sized chamber, a control element for moving said diaphragm to change the size of said chamber to move liquid out of and into said chamber and container, and a yielding element for moving the control element to either of two different limiting positions of its permitted movement.
6. In a light modifying device, the combination with a plurality of transparent plates set in juxtaposed positions and through which the light is directed, a seating element in which said plates are mounted to be relatively movable in a direction toward and from each other, means for supplying a fluid medium between said plates to spread said plates and occupy the space there-
- between, a receptacle for the fluid medium, means for moving a predetermined quantity of the fluid medium out of said receptacle and for drawing the fluid medium back into said receptacle, a yielding element for holding said last mentioned means either in the position which it occupies when said predetermined quantity of fluid is out of said receptacle or in the position which it occupies when the same predetermined quantity of fluid has been withdrawn into said receptacle, and means connecting said receptacle with said seating and the edges of said plates whereby said predetermined quantity of fluid is moved between said plates and removed therefrom as desired.
7. In a light modifying device the combination with a plurality of transparent plates arranged in substantially parallel relation with each other with their flat sides in contact with each other, the adjacent faces of said plates at their edges being beveled to form a fluid receiving recess between said plates at their peripheries, a sealing member for sealing said fluid receiving space and for urging said plates into contact with each other, and fluid pressure means for supplying fluid under pressure to said fluid space to move said plates away from each other and permit the fluid to enter the space therebetween.
8. Means adapted to control the intensity and color of projected and transmitted light, comprising a plurality of transparent plates set in juxtaposed contacting relation with each other and through which the light is to be directed, a resilient seating element in which said plates are mounted for relative movement in directions toward and from each other, means for directing a fluid medium between adjacent transparent plates to spread said plates and occupy the space therebetween, and means for forcing said fluid medium through said directing means to a position between said plates, whereby the fluid pressure moves said plates away from each other.
9. Means adapted to control the intensity and color of projected and transmitted light, comprising a plurality of transparent plates set in juxtaposed contacting relation with each other and through which the light is to be directed, a resilient seating element in which said plates are mounted for relative movement in directions toward and from each other, means for directing a fluid medium between adjacent transparent plates to spread said plates and occupy the space therebetween, and means for forcing said fluid medium through said directing means to a position between said plates, whereby the fluid pressure moves said plates away from each other, comprising a fluid chamber and fluid moving means in said chamber having means associated therewith for normally holding said fluid moving means in either of two positions when manual pressure on same is released whereby a predetermined quantity of fluid will be discharged from said chamber and directed into the space between said plates when said moving means is moved to one of its positions and will be withdrawn into said chamber upon movement of said moving means to the other of said positions.
10. Means adapted to control the intensity and color of projected and transmitted light, comprising a plurality of transparent plates set in juxtaposed contacting relation with each other and through which the light is to be directed, a resilient seating element in which said plates are mounted for relative movement in directions toward and from each other, means for directing a fluid medium between adjacent transparent plates

to spread said plates and occupy the space there-between, and means for forcing said fluid medium through said directing means to a position between said plates, whereby the fluid pressure moves said 5 plates away from each other, comprising a fluid chamber connected to said directing means and having a resilient transverse plate extending across said chamber, said plate being bowed and yieldingly held at the ends thereof with an end- 10 wise pressure, so that the plate will always tend to be bowed into either one or the other of two

similar but opposite positions, a diaphragm extending across said chamber and connected with said plate to move therewith, whereby upon release of said plate said plate as well as said diaphragm will be moved into one of said two opposite positions within said chamber to vary by predetermined amounts the size of the fluid receiving portion of said chamber.
